Inventor
S. M. Joseph.

By *Clarence O'Brien*
Attorney

UNITED STATES PATENT OFFICE.

SAMUEL M. JOSEPH, OF VINELAND, NEW JERSEY, ASSIGNOR TO JOSEPH BROTHERS,
OF VINELAND, NEW JERSEY.

COAT.

Application filed June 3, 1925, Serial No. 34,638. Renewed July 18, 1926.

The present invention relates to coats of that style commonly worn by men, and has for its principal object to provide in the coat certain novel reinforcing members for 5 increasing the life of the coat, and the style thereof.

Another specific object of the invention is to provide reinforcements of rubberized fabric, thereby preventing tearing, straining, 10 and the like, and at the same time tending to retain the portions of the coat having the reinforcements in their desired shape and formation after having been released from the stretching, straining, or any other 15 distortion.

Another specific object of the invention is to provide a rubberized reinforcing strip on the inside of the coat adjacent the top of a patch pocket which is disposed on the 20 outside of the coat in order to prevent the patch pocket from being easily torn, especially at the upper portions thereof.

Another specific object of the invention is to provide a reinforcing element on the inside of the coat, immediately below the opening to which the sleeve is attached, so as to prevent tearing as the arm enters the sleeve in putting the coat on, and to increase the 25 strength of the coat under the arm pits, at which place the coat is subject to considerable wear for obvious reasons.

A still further very important object of the invention resides in the construction of a coat which is exceedingly simple in its 30 construction, strong, durable, inexpensive to manufacture, and otherwise well adapted to the purpose for which it is designed.

With the above and numerous other objects in view, as will appear as the description proceeds, the invention resides in certain details of construction as will be hereinafter more fully described and claimed.

In the drawings:—

Figure 1 is a perspective view of the coat embodying my invention.

Figure 2 is a transverse section through one of the sleeves, and

Figure 3 is a fragmentary plan view showing the inside of a portion of the coat.

Referring to the drawing in detail, it will be seen that the body of the coat, as shown in the present example, includes the back section 5, and the two side or front sections 6, which are faced at their edges in the

usual manner as is indicated at 7 and 8. The sections 6 are attached to the edges of the sections 5 by suitable seams 9. The sleeves 10 are attached to the body in the usual manner. Patch pockets 11 are sewed to the outer surface of the sections 6, in the usual 60 manner. Thus far it will be seen that the coat is more or less of conventional construction.

Referring now particularly to my improvements for reinforcing the coat, it will 65 be seen that 13 represents two strips of rubberized material, which are applied to the inner surface of the sections 6 immediately under the arm pits. These strips 13 are applied by stitching extending adjacent its 70 lower edge while its upper edge is folded and stitched in the seam of the respective sleeve 10, as is indicated at 14.

A rubberized strip 15 is applied to the inner surface of each section 6 so that its 75 longitudinal edges are disposed one above, and one below the upper end of the adjacent patch pockets 11, as is indicated to advantage in both Figures 1 and 3. This rubberized strip extends from the seam 9, to 80 the stitching at the inner edge of the facing 7, and the end at the seam 9 is folded and sewed with the hem, while the other end is sewed with the stitching 16 of the facing 7. Stitching 17 attach the longitudinal 85 edges of each strip to its respective sections 6.

With this coat it is preferable to use a sleeve lining which extends from the intermediate elbow portion of the sleeve down 90 into the cuff 18 of each sleeve. This lining, as is shown to advantage in Figure 2 extends circumferentially in the sleeve starting from the seam 19, being tucked into the seam 20, and finally stitched as at 21 so that 95 the lining extends transversely over the major portion of the inner side of the sleeve and about half way transversely of the outer portion of the sleeve.

It is thought that the construction, utility, 100 and advantages of my improved and novel reinforcing features will now be clearly understood without a more detailed description thereof.

It is apparent that numerous changes in 105 the details of construction, in the sizes, in the materials, and in the combination and arrangement of parts may be resorted to

without departing from the spirit or scope of the invention as hereinafter claimed or sacrificing any of its advantages.

Having thus described the invention, what I claim as new and desire to secure by Letters Patent is:—

A coat of the class described including a body comprising a back section, and a pair of side sections, seams between the edges 10 of the back section, and the inner edges of the side sections, pockets on the outer sur-

faces of the side sections, and reinforcing strips applied to the inner surfaces of the side sections to extend transversely thereof, having one end folded in the seams and their 15 longitudinal edges stitched to the sections so that one edge of each section is above the upper end of the adjacent pocket and the other longitudinal edge is therebelow.

In testimony whereof I affix my signature.

SAMUEL M. JOSEPH.
